HERBERT E. GRAU AND ANDREW J. COLMERAUER, OF REDONDO BEACH, CALIFORNIA.

TUBING CATCHER.

Application filed July 31, 1926. Serial No. 126,145.

This invention has to do generally with devices applied to oil well tubing whereby such tubing may be held from dropping into the well while being pulled or set, or in the 5 event the tubing parts or its coupling threads strip at a point above the device after the tubing has been set.

The invention is particularly concerned with that type of catcher wherein the slips 10 are pivotally movable to and from operative or catching position through paths which are radial with respect to the vertical or longitudinal axis of the tubing, and even more particularly to slips which are pendant, 15 though it will be understood the invention, considered in its broader aspects, is not limited to application to catchers having these particularities.

When in inoperative or collapsed condition, the slips are annularly spaced from the 20 casing through which the tubing is lowered, but if the slips be not properly centered within the casing, or if the casing is crooked, as is frequently the case, the serrated or 25 toothed faces of the slips at one side or another are prone to contact with the casing and either cause the tubing to "hang up" or at least interfere with the smooth lowering of the tubing and cause undue wear on the 30 slips.

Therefore, it is among the objects of our 35 invention to provide a guide member on the tubing whereby the slips are centered during their progress through the casing, annular clearance thus being maintained between said slips and casing to insure that said slips do not accidentally take hold. As a further 40 feature, this centering or guide member preferably, though not necessarily, has elements engaging the slips, preferably at their free 45 ends, whereby said slips are held from movement to operative position until relative longitudinal movement in given directions has been set up between the tubing and slips.

Further objects and features of novelty 50 will be made apparent in the following detailed specification, reference being had to the accompanying drawings in which:

Fig. 1 is an elevation, partly in broken- 55 away section, of a catcher embodying our invention; the catcher being in collapsed or inoperative position;

Fig. 2 is a view generally similar to Fig. 1 but showing the catcher in expanded or operative position;

Fig. 3 is a section on line 3-3 of Fig. 1;

Fig. 4 is a section on line 4-4 of Fig. 2; and

Fig. 5 shows a variational form of catcher.

Our invention is here shown applied to a 60 catcher embodying a plurality of pivotally mounted, pendant slips which are movable radially to and from operative or expanded position, the slips preferably being so designed that they tend normally to hang in contracted or inoperative position, while an expanding or spreading member is adapted 65 forcibly to urge them to operative position when relative longitudinal movement of the slips and tubing, in given directions, is set 70 up.

Thus, in Fig. 1, where the numeral 10 designates an ordinary casing within which the tubing 11 is adapted to be set, we have shown a catcher as including an elongated 75 nipple 12 inserted in and coupled to the tubing by collars 13 and having a downwardly pointing spreader cone or cam member 14 affixed to said nipple at a point which is 80 preferably, though not necessarily, approximately midway between collars 13.

A carrier member or ring 15 is mounted 85 for movement longitudinally along that part of nipple 12 which extends between the top of cone 14 and the upper collar 13. Ring 15 has a plurality of lug pairs 16, the number 90 of pairs depending upon the number of slips used and the number of slips being optional and depending mainly upon the size of the installation; and the upper ends 95 of shanks 17 of slips 18 are pivoted to said lugs 16 by pins 19.

The slips preferably, though not necessarily, are so designed, as regards their weight disposition, that they tend normally 95 to hang approximately in the position shown in Fig. 1, that is, with their serrated faces 20 well clear of the inner wall of casing 10, and to insure that they normally will not swing outwardly into contact with the casing, we may provide the upper ends of shank 17 with angular noses 21 adapted to engage the top 22 of member 14 when the slips are collapsed. A consideration of the showing in Fig. 1 demonstrates that with these noses 100 in contact with the upper face of the cone, the slips can not swing radially outwardly unless relative longitudinal movement occurs between the cone and ring 15, and such movement does not normally occur unless the 105 tubing be suddenly dropped. However, it 110 will be understood that the provision of

noses 21 is not controlling on the invention, for we have illustrated a variational form wherein said noses are omitted without departing from the spirit and scope of our broader claims.

A guide-ring or spider for member 23 is rigidly fastened to nipple 12 at a point below spreader cone 14, this ring preferably, though not necessarily, consisting of a disk-like body member 24 having radial projections 25. The proportions of the ring are such that projections 25 normally slightly clear the inner wall of casing 10 but extend radially beyond the serrated faces of the slips when the latter are in collapsed condition. It follows that, with the slips maintained in this collapsed condition, the guide member approximately centers the slip assembly within the casing, preventing the slip assembly from canting within the casing sufficiently to bring faces 20 into engagement with the inner wall of the casing, and, if the assembly be lowered through a crooked casing, shifting the tubing and assembly so 25 annular clearance between slips and casing is preserved.

The spider-like or lug characteristic of the guide member is desirable since it offers less resistance to the lowering of the tubing, and 30 allows the passage of fluid therewith, as will be readily understood.

Preferably, the upper face of the body portion of member 23 is convex or dished, there being an annular flange 26 about the body portion which defines the concavity and provides an inwardly facing, angular shoulder 27. The lower ends 28 of the slips preferably have inwardly and downwardly inclined faces 29 which are substantially 35 complementary to faces 27, and the various parts are so proportioned that the distance d between the casing and the high point 29 of shoulder 27 is less than the distance d' between the serrated face 20 and the lowermost point 30 of slip shoulder 29; it following that when the slips are lowered into horizontal alignment with the guide member, or the guide member raised into horizontal alignment with the slip-ends, said slips are 40 guided into the concavity at the top of the guide-member rather than sliding down over the outside of flange 26. Preferably, when ring 15 is in its lowermost position, that is, when noses 21 rest on top the cone wedge, there is slight clearance between the end of the slips and guide-member 23, though this 45 clearance is not essential to the invention. It will be seen that as long as the parts are in the relative position shown in Fig. 1, flange 26 serves to hold the slips in collapsed or inoperative position even though ring 15 be raised slightly, the guide-member thus serving the dual function of a centering means and a slip retention means.

As the tubing is lowered through the cas-

ing, and unless the drop of the tubing proper be suddenly accelerated, the parts remain in the position shown in Fig. 1. However, should the tubing be suddenly dropped, either intentionally or by reason of a parting of the tubing or stripping of the tubing threads at a point above the catcher, cone 14 and member 23 will move downwardly with respect to ring 15 and slips 18, for reasons that are apparent, noses 21 and the ends of slips 18 thus being released from operative association with cone 14 and member 23, respectively; the slips thus being released so they may travel radially outwardly with respect to the longitudinal axis of the tubing. 70 This radial movement is forcibly accomplished by the action of the spreader cone against the inner, complementarily inclined faces 18' of the slips, said slips moving pivotally about pins 19. The slips are thus 75 driven by the spreader forcibly against the inner wall of the casing, the serrations on face 20 tightly gripping the casing as illustrated in Fig. 2, and the catcher assembly thus holding the tubing from further drop, 80 as will be readily understood, it being apparent that the slips are wedged tightly between the cone and the casing and hence, in effect, between the tubing and casing.

An upward pull then exerted on the tubing, imparted either through the tubing above, if the latter be intact, or by a fishing tool, first serves to draw the spreader cone upwardly with respect to the slip assembly, whereupon they normally tend to swing inwardly by gravity, member 23 finally reaching the position shown in Fig. 1 and noses 21 finally being engaged by the cone to hold the slips in inoperative position. In the event the slip teeth tend to cling to the casing after the cone is partially raised, the contact of the cone with the noses 21 and the contact of shoulder-face 27 with slip-face 29 positively moves the slips inwardly and frees the serrations from the casing. Thereafter, 100 the tubing may again be lowered with the slips correctly centered and held from unintentional engagement with the casing, or the lift of the assembly may be continued without engagement between said slips and 105 casing.

In Fig. 5 we have illustrated a modification wherein all parts similar to those shown in the other figures are given the same reference numeral with the addition of the exponent "a". The variation consists in the elimination of noses 21, the ends of shanks 17^a being in the form of bosses 40 pivotally connected by pins 19^a to ring 15^a. In this instance, dependence is had entirely upon 120 shoulder 27^a of flange 26^a for releasably holding slips 18^a in collapsed position, the weight of the slips and ring 15^a being taken entirely by member 23^a, though this 125 particular method of ring and slip support is 130

not controlling on this variation of the invention.

The operation of the variation shown in Fig. 5 is the same as that described in connection with the other views, with the exception that the positive return of the slips to inoperative position, in the event the slips do not gravitate to collapsed position when the tubing starts upwardly, is accomplished 10 solely through engagement of shoulder 27^a with shoulder 29^a.

It will be understood the drawings and description are to be considered merely as illustrative of and not restrictive on the 15 broader claims appended hereto, for various changes in design, structure and arrangement may be made without departing from the spirit and scope of said claims.

We claim:

- 20 1. In a tubing catcher embodying slips supported by the tubing and movable radially with respect to the tubing axis into and out of operative position, a guide member on the tubing below the slips and extending radially beyond the slips when said slips are in inoperative position, and releasable means adapted to hold said slips in inoperative position, said slips being engageable by the guide member.
- 25 2. In a tubing catcher embodying slips supported by the tubing and movable radially with respect to the tubing axis into and out of operative position, a guide member on the tubing below the slips and extending radially beyond the slips when said slips are in inoperative position, and means on the guide member adapted to hold said slips releasably in inoperative position.
- 30 3. In a tubing catcher embodying pendant slips supported by the tubing and movable radially with respect to the tubing axis into and out of operative position, a guide member on the tubing below the slips and extending radially beyond the slips when said slips are in inoperative position, and releasable means adapted to hold said slips in inoperative position, said slips being engageable by the guide member.
- 35 4. In a tubing catcher embodying pendant slips supported by the tubing and movable radially with respect to the tubing axis into and out of operative position, a guide member on the tubing below the slips and extending radially beyond the slips when said slips are in inoperative position, and means adapted to hold said slips in inoperative position, said slips being engageable by the guide member.
- 40 5. In a tubing catcher embodying pendant slips supported by the tubing and movable radially with respect to the tubing axis into and out of operative position, a guide member on the tubing below the slips and extending radially beyond the slips when said slips are in inoperative position, and means on the guide member adapted to hold said slips releasably in inoperative position.
- 45 6. In a tubing catcher embodying pendant slips supported by the tubing and movable radially with respect to the tubing axis into and out of operative position, a guide member on the tubing below the slips and extending radially beyond the slips when said slips are in inoperative position, and means on the guide member adapted to hold said slips releasably in inoperative position.
- 50 7. In a tubing catcher embodying pendant slips supported by the tubing and movable radially with respect to the tubing axis into and out of operative position, a guide member on the tubing below the slips and extending radially beyond the slips when said slips are in inoperative position, and means on the guide member adapted to hold said slips releasably in inoperative position.

radially with respect to the tubing axis into and out of operative position, a guide member on the tubing below the slips and extending radially beyond the slips when said slips are in inoperative position, and means on the 55 guide member adapted to hold said slips releasably in inoperative position.

5. In a tubing catcher embodying pendant slips supported by the tubing and movable radially with respect to the tubing axis into and out of operative position, a member on the tubing adapted to coact with the lower ends of the slips to hold them releasably in inoperative position, and radial extensions 60 on said member extending radially beyond 65 said slips when the latter are in inoperative position.

6. In a tubing catcher embodying pendant slips supported by the tubing and movable radially with respect to the tubing axis into and out of operative position, a spider on the tubing below the slips, and an upstanding flange near the outer edge of the spider, the lower, free ends of the slips being adapted to lie in horizontal alinement with 70 the inwardly facing shoulder formed by the flange, when said slips are in inoperative position.

7. In a tubing catcher embodying slips supported for limited longitudinal movement along the tubing and movable radially with respect to the tubing axis into operative position by virtue of relative longitudinal movement between the tubing and slips in given directions, a guide member on the tubing below the slips and extending radially beyond the slips when the latter are in inoperative position, and means on the guide member adapted to force the slips radially from operative to inoperative position, said 80 last-named means being operable by virtue of relative longitudinal movement of the tubing and slips in directions opposite the given directions.

In witness that we claim the foregoing we 85 have hereunto subscribed our names this 17th day of July, 1926.

HERBERT E. GRAU.
ANDREW J. COLMERAUER.
